UNITED STATES PATENT OFFICE.

GUSTAV O. J. KLEVEN, OF SALT LAKE CITY, UTAH.

MECHANICAL STOKER.

1,247,969.

Specification of Letters Patent. Patented Nov. 27, 1917.

Application filed November 15, 1916. Serial No. 131,575.

To all whom it may concern:

Be it known that I, GUSTAV O. J. KLEVEN, a citizen of the United States, residing at Salt Lake City, in the county of Salt Lake 5 and State of Utah, have invented certain new and useful Improvements in Mechanical Stokers, of which the following is a specification.

My invention relates to mechanical stokers, and has for its object to provide a stoker by which coal may be mechanically fed into a boiler furnace and so distributed that better combustion may be secured and thereby greater heat provided under the 15 boiler and less obnoxious gases and smoke escape from the flue or smoke stack.

These and other objects which are apparent I accomplish with my invention which is illustrated in the accompanying 20 drawings in which similar letters and numerals of reference indicate like parts throughout the several figures, and as described in the specification forming a part of this application and pointed out in the 25 appended claims.

In the drawings in which I have shown a substantial embodiment of my invention, Figure 1 is a longitudinal vertical section of the device in place in the boiler furnace. 30 Fig. 2 is an elevation of the front end of a boiler with parts cut away to show the present invention in place under said boiler. Fig. 3 is a plan view of the device. Fig. 4 is a detail of the chain belt links and pivot 35 rods. Fig. 5 is a detail showing the screw feed and portions of the bridge wall.

I am aware that mechanical stokers have been used to feed coal into boiler furnaces, and to introduce the coal at the back of the 40 furnace and mechanically move it forward into the blaze. By means of the present invention I introduce hot air in a novel manner at the front of the fire box to aid combustion. The bridge wall is constructed to 45 support and protect the coal chute and screw feed. The present invention consists of two rails 1 upon which the traveling grate may be moved longitudinally, and which are placed at the sides and on the floor of the 50 ash box A. The boiler shown at B may be of any type of flue boilers and is mounted upon the ordinary wall in the usual manner. The front doors needed are the cleanout door C, the door D commonly used for feeding 55 coal into the furnace but which I use only as a convenience in placing my stoker. The

traveling grate consists of a frame 2 that is mounted on flanged wheels 3 which rest upon said rails 1. Two octagonally shaped rollers 5 are journaled on said frame 2, and the shaft of one of them is extended and upon which is fastened a gear wheel 4 through which motion is imparted to said rollers 5. A chain belt O is carried over said rollers 5, which belt consists of metal links 6 having transverse holes therein, through which the pivot rods 7 are passed and fastened. Each of said rods are of sufficient length to form the pivot for all the laterally adjacent links 6 and other parallel rods and links are used to form a chain the full width of said rollers 5 and of a length sufficient to encircle the two rollers. The coal is fed onto the said belt O by means of a screw 8 which is carried and operated in a tubular 75 casing 9. The said casing 9 has spaced apart walls to form a water jacket around said screw 8 and to protect both the screw and casing from the extreme heat which both are subjected to. The walls of said casing 9 do 80 not meet on the front side and are extended and one bent at right angles to form a feed channel 10 through which the coal is fed onto the said belt. A water pipe 11 is connected with the interior of said water jacket- 85 ed wall of said casing through which water is allowed to flow. The bridge wall E is constructed partially around said casing and inclined toward the rear to form a combustion chamber F. Air conduits G and H 90 are provided, each having its ingress extended through the side wall of said boiler furnace and a horizontal portion 12 of conduit G and 13 of conduit H are passed across the furnace fire box near the front end of 95 the said chain belt and spaced above it. In each of said conduits and in the said portions 12 and 13 respectively are provided vertical air tubes 14, through which heat from the fire may pass and by which the air 100 passing through the said conduits G and H is heated. The egress ends of said conduits G and H are passed toward the front of the furnace wall and enter said furnace near the front and below the said chain belt O. A 105 hopper 15 is provided on one end portion of and opening into the interior of said casing 9, through which coal is fed into said casing. The shaft of said screw 8 is extended beyond the said hopper 15, and a gear wheel 16 110 is secured on said shaft by which motion is imparted to said screw to move coal

through and out of said casing 9 onto the said belt O. The operation of my stoker is as follows: motion having been imparted to said gear 16 and gear wheel 4 and through them to the said screw 8 and chain belt O, coal is supplied in the said hopper 15 and is moved longitudinally in said casing 9. Some of the coal will be immediately discharged through the said channel 10 onto the belt O, while some of it will be moved along and will be discharged at other points on said belt. In that way and by means of said screw, casing and channel 10, a continuous thin layer of coal will be fed onto said belt. The fire having been started on the said belt, the coal that is fed from said channel 10 will be carried forward on the said belt slowly, through the blaze and consumed. Hot air will enter said furnace 20 through said conduits G and H and will pass upward through said belt and aid combustion. A portion of the ashes and cinders from said combustion will fall through said chain belt O as through an ordinary grate, the balance will fall at the front below the dead plate 17, and may be taken from the ash pit through the door C. The grate may be taken out through the ash or cleanout door for repairs.

Having thus described my invention I desire to secure by Letters Patent and claim:

1. A mechanical stoker comprising a wheel supported frame; octagonally shaped

rollers journaled on said frame; a link metal belt carried over said rollers and with its line of travel toward the front; a casing supported by and partially covered by the bridge wall of the furnace and having a discharge channel longitudinally formed as a portion of the circumference thereof; a screw feed operable in said casing; a hopper on one end portion of said casing; air conduits supported above said belt and with the air exits below and at the front end of said belt; and means to rotate said rollers and said screw on their respective axes.

2. A mechanical stoker comprising a longitudinally movable frame; rollers journaled on said frame; a grate belt carried over said rollers and with its line of travel toward the front roller; a casing supported by and partially covered by the bridge wall of the furnace and having a discharge channel longitudinally formed thereon; a screw operable in said casing; a hopper on one end portion of said casing; air conduits supported above said belt and with the air exits below and at the front end of said belt; vertical air flues in said air conduits; and means to rotate said rollers and said screw on their respective axes.

In testimony whereof I have affixed my signature in presence of a witness.

GUSTAV O. J. KLEVEN.

Witness:

SAM RANNEY.
